[57] CLAIM

The ornamental design for a gun rack, as shown and
described.

DESCRIPTION

FIG. 1 is a perspective view of a gun rack showing my
new design;

FIG. 2 is a front elevation of a gun rack, the rear view
being a mirror image thereof;

FIG. 3 is a side elevation thereof, the opposite side
being a mirror image of the side shown;

FIG. 4 is a top plan view thereof; and,

FIG. 5 is a bottom plan view thereof.

FIG. 4

FIG. 1

FIG. 2

FIG. 3

FIG. 5
